UNITED STATES PATENT OFFICE.

LOUIE C. KAHL, OF WATERBURY, CONNECTICUT, ASSIGNOR TO THE WATERBURY MACHINE COMPANY, OF WATERBURY, CONNECTICUT, A CORPORATION OF CONNECTICUT.

FASTENER.

SPECIFICATION forming part of Letters Patent No. 771,912, dated October 11, 1904.
Application filed April 18, 1904. Serial No. 203,651. (No model.)

To all whom it may concern:

Be it known that I, LOUIE C. KAHL, a citizen of the United States, residing at Waterbury, in the county of New Haven and State 5 of Connecticut, have invented certain new and useful Improvements in Fasteners, of which the following is a specification, reference being had therein to the accompanying drawings.

10 My invention relates to new and useful improvements in fasteners, and refers more particularly to fasteners of the ball-and-socket type.

15 It is the object of my invention, among other things, to construct a fastener in which the socket will have the maximum yielding capacity when the ball is being placed therein or taken therefrom without impairing its strength, the cheapness of its manufacture, 20 or its holding qualities.

25 To these and other ends my invention consists in the fastener having certain details of construction and combination of parts, as will be hereinafter described, and more particu- larly pointed out in the claim.

Referring to the drawings, in which like numerals of reference designate like parts in the several figures, Figure 1 is an elevation of the socket of my invention with the re- 30 taining-washer and fabric to which it is applied in section. Fig. 2 is an elevation of the ball. Fig. 3 is a plan view of the socket, and Fig. 4 is a vertical section thereof upon line A B of Fig. 3.

35 In carrying out my invention I construct a socket member 1 with a substantially cylindrical solid bottom barrel portion 2 and a flange portion 3, the neck 4 of the barrel portion being reduced in diameter at its stud or 40 ball receiving end and rounded so as to form a flaring throat 5 upon the inside. Through the flange 3, adjacent to the outer edge thereof and the sides of the barrel portion 2, midway of its length, are a plurality of enlarged open-

ings 6, and connecting said enlarged openings 45 are the slots 7, narrower than the openings. Only that portion of the socket known as the "throat" is required to be yielding in order to permit the ready passage of the ball therethrough, and in my invention I obtain the 50 maximum flexibility by taking out considerable of the metal at the ends of the slots 7, thereby permitting the parts to yield throughout the whole length of the slots and not just at the junction of the barrel and flange as in 55 fasteners heretofore made.

Slotted fasteners have been made prior to my invention; but I am yet to be advised of one being made where the slots terminate in openings of greater width than said slots and 60 do not extend through either the full width of the flange or the length of the barrel.

My fastener is secured to the fabric (represented by the numeral 8) with a washer 9, that is placed over the end of the barrel, which is 65 then spread outwardly a little at its extreme end into the countersink in said washer, as shown in Fig. 1.

The ball 10 can be of any preferred construction and need not be described here in 70 detail.

There are minor changes and alterations that can be made within my invention aside from those herein shown and suggested, and I would therefore have it understood that I 75 do not limit myself to the exact construction herein shown and described, but claim all that falls fairly within the spirit and scope of my invention.

Having described my invention, what I 80 claim as new, and desire to secure by Letters Patent, is—

In a device of the character described, the combination with a fastener of a socket there- 85 in comprising a substantially cylindrical bar- rel portion having a reduced inwardly-curved throat-forming section at the stud-receiving end thereof, a flange portion extending out-

wardly from said portion of the inwardly-curved section of the barrel, and being provided with a plurality of enlarged openings therethrough, said barrel portion being also provided with enlarged openings substantially centrally disposed therein and having slots narrower than the openings leading therefrom through the throat-forming section to the

openings in the flange, substantially as described.

In testimony whereof I affix my signature in presence of two witnesses.

LOUIE C. KAHL.
